(57) **CLAIM**

The ornamental design for a circular island, as shown and described.

DESCRIPTION

FIG. 1 is a front perspective view of a circular island according to an embodiment of the present invention;

FIG. 2 is a front plan view of the circular island shown in FIG. 1, the rear plan view of the circular island shown in FIG. 1 is identical to the front plan view;

FIG. 3 is a left side plan view of the circular island shown in FIG. 1, the right side plan view of the circular island shown in FIG. 1 is identical to the left side plan view; FIG. 4 is a top plan view of the circular island shown in FIG. 1;

FIG. 5 is a bottom plan view of the circular island shown in FIG. 1;

FIG. 6 is a front perspective view of a circular island according to a second embodiment;

FIG. 7 is a front plan view of the circular island shown in FIG. 6;

FIG. 8 is a rear plan view of the circular island shown in FIG. 6;

FIG. 9 is a right side plan view of the circular island shown in FIG. 6; the left side plan view of the circular island shown in FIG. 6 is a mirror image of the right side plan view;

FIG. 10 is a top plan view of the circular island shown in FIG. 6;

FIG. 11 is a bottom plan view of the circular island shown in FIG. 6;

FIG. 12 is a front perspective view of a circular island according to a third embodiment;

FIG. 13 is a front plan view of the circular island shown in FIG. 12, the rear plan view of the circular island shown in FIG. 12 is identical to the front plan view;

FIG. 14 is a left side plan view of the circular island shown in FIG. 12, the right side plan view of the circular island shown in FIG. 12 is identical to the left side plan view;

FIG. 15 is a top plan view of the circular island shown in FIG. 12; and,

FIG. 16 is a bottom plan view of the circular island shown in FIG. 12.

The broken lines shown herein form no part of the claimed design.
